COMBINED HANDLE, ACCESS DOOR AND CONTROL PANEL FOR AN ELECTRIC CONTROLLER OR SIMILAR ARTICLE

David L. Swindler, Bedford, Ohio, assignor to Square D Company, Park Ridge, Ill., a corporation of Michigan

Filed Sept. 24, 1964, Ser. No. 81,866

Term of patent 14 years

(Cl. D26—13)

Fig. 1.

Fig. 3.

Fig. 2.

FIG. 1 is a perspective view of a combined handle, access door and control panel for an electric controller or similar article showing my new design;

FIG. 2 is a reduced scale front elevational view thereof; and

FIG. 3 is a reduced scale right side elevational view thereof.

The dominant features of my design reside in the full line portion of the drawing, the top and bottom edges of the door being shown in dotted lines to indicate that the door may be of indeterminate length. The cabinet shown in dotted lines is for illustrative purposes only.

I claim:

The ornamental design for a combined handle, access door and control panel for an electric controller or similar article, substantially as shown and described.
